(57) **CLAIM**

The ornamental design for an apparatus for recognition of biometric information, as shown and described.

DESCRIPTION

FIG. 1 is the front perspective view of an apparatus for recognition of biometric information showing the claimed design;

FIG. 2 is the front view thereof;

FIG. 3 is the rear view thereof;

FIG. 4 is the left-side view thereof;

FIG. 5 is the right-side view thereof;

FIG. 6 is the top plan view thereof; and,

FIG. 7 is the bottom plan view thereof.

1 Claim, 6 Drawing Sheets

FIG. 1

FIG. 2

FIG. 3

FIG. 4

FIG. 5

FIG. 6

FIG. 7
